UNITED STATES PATENT OFFICE.

WENDELIN P. SENG, OF CHICAGO, ILLINOIS, ASSIGNOR TO THE SENG COMPANY, OF CHICAGO, ILLINOIS, A CORPORATION OF ILLINOIS.

FOLDING END SECTION FOR BEDS.

1,126,303.

Specification of Letters Patent. Patented Jan. 26, 1915.

Application filed December 8, 1913. Serial No. 805,272.

To all whom it may concern:

Be it known that I, WENDELIN P. SENG, a citizen of the United States, and a resident of Chicago, in the county of Cook and State 5 of Illinois, have invented a Folding End Section for Beds, of which the following is a full and complete specification.

The primary object of my invention is to provide an improved folding end-section 10 or head-rest especially adapted for application to metal cots or to folding bed-frames such as is used in connection with the conventional type of sofa-bed or davenport in which the bed sections are foldable upon 15 each other so as to be confined in a box or receptacle therefor beneath the seat of the sofa or davenport; whereby in the present instance the end-section or head-rest may be folded down upon the mattress so as not to 20 interfere with the folding of the bed sections and their confinement within the box, and also serve to assist in holding the mattress firmly against the metal bed-frame sections during the operation of folding and 25 unfolding the bed.

My invention consists in providing a light and durable folding end-section or head-rest comprising a frame hingedly connected at its ends to the metal bed-frame section so 30 as to swing or fold thereon, in connection with a spring for maintaining said end-section or head-rest in either its folded or extended position.

My invention further consists in the particular construction of the frame constituting the folding end-section or head-rest, all as hereinafter fully described and specifically set forth in the appended claims.

In the accompanying drawings: Figure 1 40 is an end view showing the application of my invention to a metal bed-frame section, the end-section or head-rest being in extended position. Fig. 2 is a sectional view through the center of the parts shown in Fig. 1, the end-section or head-rest being 45 shown in folded position.

My invention may be applied to the bed-frame section or sections of any type of folding-bed, cot, couch, &c., although in the

present instance it is shown as applied to 50 a metal bed-frame section of a folding-bed in which the end pieces are each made of an angle-bar 5, connected by a tubular bar or rail 6, the fabric or spring bed-bottom A, being connected to said end pieces in the 55 usual manner.

In carrying out my invention the end piece or angle-bar 5 is provided near its ends with short uprights or standards 7, 7, rigidly secured thereto in any suitable manner, in the present instance by a single rivet 8, inasmuch as the squared lower end of the standard is seated on the bottom flange of the angle-bar and the attaching-rivet passes through the vertical member thereof. Each 60 upright or standard 7 is preferably in the form of an angle-plate, one member, as 7^a, of which rests against the vertical member of the end-piece or angle-bar of the bed-frame, and the other member, as 7^b, projects 65 inwardly at a right-angle therefrom, for the particular purpose hereinafter explained.

The end-section or head-rest, 9, is hinged or pivoted at its ends to the inwardly-projecting member 7^b of the angle-plates or standards below the upper ends thereof and a slight distance in advance of the member 7^a, whereby when said end-section is raised the outward movement thereof will be limited to a position slightly beyond the vertical, as indicated in dotted lines in Fig. 2. The end-section is formed of wire, of a proper gage, and consists of a loop or inverted U-shape frame 9^a having terminal eyes 9^b, 9^c, 80 and an inner frame or brace 10 also formed of wire and of a suitable design, connected to said U-shape frame. The wire forming the brace 10 is in the present instance bent upon itself to form a center V-shape extension or loop 10^a, and end members 10^b projecting at an acute angle from the sides of the said V-shape extension or loop, the terminals 10^c of the end members being bent 85 abruptly and laterally to pass through and 90 beyond the eyes 9^b of the U-shape frame and through corresponding openings formed in the members 7^b of the standards 7, where-

by to not only connect these parts but also provide pivots or gudgeons by which the end-section or head-rest is pivoted or hinged to the uprights. The frame 9^a and brace 10 are further connected together, at intermediate points, by clips 11, which embrace the wire of the frame and wire of the brace, engaging the latter at the bends between the V-shape center and end-members, the wire 10 of the frame at these points being depressed, as shown at 9^c, to receive the clips, so that in conjunction with the adjoining bends of the wire brace the parts of the end-section or head-rest are thereby rigidly connected. 15 In this manner, as will be observed, the end-section or head-rest is hinged or pivoted to the standards (preferably being sprung into position) so that it may fold down upon the bed-frame section or mattress thereon, and 20 when swung upwardly it will rest against the upper ends of said standards at a slight rearward inclination. It will be also observed that the end-section or head-rest is of light, strong, and durable construction, and 25 by connecting the two parts thereof in the particular manner herein shown and described the ends of the wire-brace form the means of pivotal connection to the short uprights or standard on the metal bed-frame 30 section; such means in the present instance providing for readily and conveniently applying the end-section or head-rest, inasmuch as the ends of the wire-brace are movable in the eyes of the frame but are held 35 normally projected by the spring tendency of the wire of which the end members of said brace are formed. To maintain this end-section or head-rest in either its folded or extended position a helical spring 12 is 40 connected at one end to the V-shape center of the brace and at its other end to the upper part of the angle-bar or end piece of the bed-frame section on a line beyond the standards, so that the tension of the spring 45 will exert a holding strain when said end-section or head-rest is swung past the vertical in either direction.

The device may be applied to any form of bed, cot, couch, &c., but as heretofore 50 stated is especially adapted for application to that type of folding metal bed-frame sections employed in connection with sofa-beds or bed-davenports, to provide folding ends therefor.

55 Having thus described my invention, I claim.

1. In combination, with a bed-frame, having transversely opposite bearings, an end-section or head-rest comprising a substantially U-shaped outer frame having eyes at 60 its ends, an angular wire brace inclosed by and connected intermediate its ends to the U-shaped frame and having end-members with short lateral terminals passing through

and beyond the aforesaid eyes of the same 65 and into the opposite bearings of the bed-frame, and a spring connected to the said wire brace and the bed-frame, whereby to exert tension on the brace when thrown to either side of its perpendicular, said spring 70 being inclosed by the U-shaped frame.

2. In combination, with a bed-frame, having transversely opposite bearings, an end-section or head-rest comprising a substantially U-shaped outer frame having eyes at 75 its ends, and an inner angular wire brace connected intermediate its ends to the frame and having end-members with short lateral terminals passing through and beyond the aforesaid eyes and into the opposite bearings 80 of the bed-frame.

3. In combination, with a bed-frame, having transversely opposite bearing-openings, an end-section or head-rest, comprising an outer wire frame of substantially U-shape 85 having terminal eyes corresponding to the aforesaid bearing-openings, and an inner wire brace having a central portion of substantially V-shape and at each side of the same inclined terminals laterally bent to 90 form bearings, said bearings passing through the eyes of the outer frame and through and beyond the same into the bearing-openings of the bed-frame, and clips connecting the outer frame and the brace at 95 each side of the central V-shaped portion of the latter.

4. In combination, with a bed-frame, angular end-standards rising therefrom and provided with bearing-openings, an end- 100 section or head-rest comprising an outer wire frame of substantially U-shape having terminal eyes corresponding to the aforesaid bearing-openings in the standards, an inner wire brace having a central portion 105 of substantially V-shape and at each side of the same inclined terminals laterally bent to form bearings, said bearings passing through the eyes of the outer frame and beyond the same into the bearing-openings 110 of the standards, clips connecting the outer frame and the brace at each side of the central V-shaped portion of the latter, and a coiled spring connected to the V-shaped portion of the brace and to the bed-frame, 115 whereby to exert tension on the end-section or head-rest when at either side of the perpendicular.

5. In combination with a bed-frame having transversely opposite bearings, an end- 120 section or head-rest comprising a substantially U-shaped outer frame having eyes at its ends, and an inclosed wire-brace doubled upon itself to form a central extension and having its terminals laterally disposed to 125 form bearings and passed through and beyond the eyes of the U-shaped frame and into the bearings of the bed-frame, connec-

tions between the U-shaped frame and the wire-brace at each side of said central extension of the latter, and a spring connected to said central extension of the wire-brace and to the bed-frame, whereby said head-rest may be yieldingly held at each side of its vertical position.

In testimony whereof I have signed my name to this specification in the presence of two subscribing witnesses.
